UNITED STATES PATENT OFFICE.

GEORGE M. HASEN, OF ST. LOUIS, MISSOURI.

REEL FOR SACK-TYING MACHINES.

Application filed April 7, 1922. Serial No. 550,532.

To all whom it may concern:

Be it known that I, GEORGE M. HASEN, a citizen of the United States, and resident of St. Louis, Missouri, have invented certain new and useful Improvements in Reels for Sack-Tying Machines, of which the following is a specification.

This invention relates to improvements in reels for sack tying machines, and has for its object a structure on which is placed a coil of wire or other material, and placed in a convenient position relative to the feeding machine of a sack tying machine; the said reel being so constructed as to revolve slowly as the wire is being fed through the tying machine.

A further object of my invention is to construct a reel consisting preferably of a staff on which is revolubly mounted a coil supporting frame on which the coil of wire or other material is supported and the same so arranged as to provide free movement during the unwinding of the coil and to provide for the tension and slack, at the same time preventing the wire from kinking or twisting during the un-winding process.

Figure 1, is a vertical central sectional view of my improved reel.

Fig. 2, is a top plan view of the same.
Fig. 3, is a detail sectional view of the upper bearing made use of.

Fig. 4, is a perspective view of my invention.

In the general construction of my invention I provide a reel consisting of a base or foot section 5, on which is firmly supported a staff 6. Over this staff is placed a coil supporting frame consisting of a platform or table 7 provided with a central opening 8 which is of a diameter somewhat larger than the staff 6.

On the periphery of the platform or table 7 and at suitable intervals apart I provide arms 9, and on the top of the arms is attached a rail or band 10.

On the table and at suitable intervals apart I provide a plurality of standards 11, which are inclined and the upper ends are attached to a top 11', thus the upper end of the extension is of smaller diameter than the base or the bottom, where the standards are attached to the platform.

On the under side of the top 11', I provide a socket bearing 12, in this bearing is placed a bearing ball 13 which is seated in a depression 14 formed in the socket, and a de-

pression 15 formed in the top of the staff; thus the entire weight of the coil supporting frame is suspended on the top of the staff and by means of the bearing ball a great portion of the friction is eliminated.

On the bottom of the platform I place a bearing plate or disc 16 which is provided with a central opening 17 of a size sufficiently large to fit around the periphery of the staff and act as a semi-frictional bearing.

This structure of a reel is used in conjunction with a sack tying machine and on the platform between the standards 11 and the arms 9 is placed the coil of wire as that indicated by dotted lines in Fig. 4.

The end of the wire is fed into the bearing mechanism of the tying machine and during the operation, as the wire is fed through the machine the pulling effect on the wire causes a slow revolving action on the reel and while the wire is being unwound it has a tendency to rise upwardly on the inclined body as that shown by dotted lines in Fig. 4, and during this un-winding action the reel is permitted to revolve slowly and allows for the spreading of the wire in the event of sudden stoppage and too much play or sag. It likewise permits the wire to un-wind evenly and prevents kinking and twisting, and by means of the arms 9 and rail 10, it likewise keeps the wire within that section of the reel even, in the event the reel should operate a little more in advance of the feeding of the wire in the machine.

The reel is placed in any convenient location to the feeding mechanism of the tying machine.

Having fully described my invention what I claim is:

1. A reel used in conjunction with sack tying machines comprising a platform, a rail carried thereby, a plurality of standards mounted on the platform and extending upwardly; a top secured to the upper ends of the standards, said top being of smaller diameter than the base, a ball journal supported under the top; a standard projecting into the journal and on which the reel is revolubly mounted; a bearing plate supported on the bottom of the platform and in loose communication with the periphery of the staff, and the base on which the standard is rigidly mounted, substantially as specified.

2. A reel used in conjunction with sack tying machines, comprising a circular plat-

form 7, arms 9 extending upwardly from the periphery of said platform, a band 10 connected to the top of the arms, a plurality of standards 11 connected to the platform 5 and spaced a reasonable distance from the arms 9, a top 11' connected to the top of the standards, a socket bearing 12 connected to the underside of the top 11', a bearing ball 13 located in the socket, a stationary supporting shaft 6 having a depression 15 in which the bearing ball is seated, and a bear-

ing plate 16 located on the bottom of the platform and surrounding the shaft 6, substantially as specified.

In testimony whereof, I have signed my 15 name to this specification, in presence of two subscribing witnesses.

GEORGE M. HASEN.
